E. P. BAIRD

LOCK

Filed May 12, 1919

Inventor:

Edward P. Baird
By Finsgerlach Atty

Witness: Fig. 8.

A. J. Sauer.

UNITED STATES PATENT OFFICE.

EDWARD P. BAIRD, OF EVANSTON, ILLINOIS. ASSIGNOR TO CHICAGO CABINET LOCK COMPANY, OF CHICAGO, ILLINOIS, A CORPORATION OF ILLINOIS.

LOCK.

Application filed May 12, 1919. Serial No. 296,289.

To all whom it may concern:

Be it known that I, EDWARD P. BAIRD, a citizen of the United States, and a resident of Evanston, in the county of Cook and State of Illinois, have invented certain new and useful Improvements in Locks, of which the following is a full, clear, and exact description.

The invention relates to locks and more particularly to cylinder locks of that type in which plate-tumblers are used.

The object of the invention is to provide a lock of this type which is efficient in operation and which cannot be picked or operated without a correct key.

The invention consists in the several novel features hereinafter set forth and more particularly defined by claims at the conclusion hereof.

In the drawings: Fig. 1 is a vertical longitudinal section of a lock embodying the invention. Fig. 2 is a section taken on the line 2-2 of Fig. 1. Fig. 3 is a horizontal longitudinal section. Fig. 4 is a rear end elevation and Fig. 5 is a view similar to Fig. 1, the key being inserted. Fig. 6 is a detail of one of the tumblers. Fig. 7 is a detail side elevation of one of the spring plates for holding the tumblers in assigned position. Fig. 8 is a sectional view of a modification with shoulders 21 omitted.

A cylindrical casing 8 is adapted to rotatably sustain a carrier 9 in which plate-tumblers 10 are mounted to slide transversely into pockets or openings 12 formed in the casing, so that when the end of any of the tumblers extend into the casing, the carrier cannot be rotated and so that when the tumbler is held in proper position by a key all of the tumblers will be retracted from the casing to render the carrier rotatable by a key 13. Studs 14 are secured to the rear end of the carrier and may be connected to operate the bolts of the lock in any manner, as well understood in the art.

In the exemplification of the invention shown, the tumblers 10 are arranged in series which are spaced apart by ribs 15 in the guide-way 16 in the carrier for the tumblers. The key 13 is provided with similarly shaped edges 13^a and 13^b to pass through the slots 10^a in the tumblers and so that the key is adapted to move each tumbler

transversely in either direction. A spring-plate 18 is interposed between a pair of the tumblers of each series to cause the latter to be frictionally held in the guide-way 16. This friction-plate holds the tumblers so that force will be required to move the tumblers in either direction, is normally curved, as shown in Fig. 7, and is provided with a slot through which the key passes so that it will be withdrawn from the carrier with the tumblers.

The front and rear portions of the casing are provided with a suitable slot 19 to receive and hold the key in such manner that, when the carrier is released, it can be rotated by the key.

An important feature of the present invention consists in providing means on the tumblers for holding them against transverse movement if attempt is made to pick the tumblers into released position and to hold them there by rotation of the carrier. For the purpose of preventing this from being done, each tumbler is provided at each of its ends and at each side thereof with a stop lug 20. In practice, attempts are sometimes made to insert a wire through the key-slot 19 and to successively move the tumblers transversely into released position and to ascertain or frictionally hold them in such position by exerting slight rotative pressure upon the carrier.

When that is done and the tumblers are provided with stop-lugs 20, said lugs will, as the result of the rotative pressure on the carrier, lap one of the shoulders 21 formed in guide-way 12 in the casing. As a result, when rotative pressure is exerted upon the carrier, the stop-lugs of all tumblers not in releasing position will, at one side or the other of the carrier, interlock with the casing and be secured against movement in the guide-way until the carrier is rotated to bring the tumblers in neutral position. This feature thus provides means for preventing the plate-tumblers from being picked.

In operation, the tumblers will be in irregular position, as shown in Fig. 1. As the key 13 is withdrawn, each tumbler will project either at one end or the other into the casing to secure the carrier against rotation. When a key 13 is inserted, it will

withdraw all of the tumblers into the carrier and release the latter for rotation by the key.

In Fig. 8, there is shown a modification 5 of the invention in which the shoulders 21 are omitted and the stop lugs 20, in lieu of engaging such shoulders, will engage a peripheral portion of the carrier adjacent the guide-way 16 when the carrier is subjected to rotative pressure. It will be understood that these tumblers have a slight play 10 in the carrier, so that when the stop-lug 20 at one side engages the side of the recess 12, the stop lug at the other side will be forced to lap a peripheral portion of the carrier.

The invention is not to be understood as restricted to the details set forth, since these may be modified within the scope of the 20 appended claims, without departing from the spirit and scope of the invention.

Having thus described the invention, what I claim as new and desire to secure by Letters Patent, is:

1. In a cylinder lock, the combination of 25 a casing, a carrier rotatable in the casing having a transverse guideway therein extending therethrough, key-operable plate tumblers, transversely slidable in said guideway and into interlocking relation with the casing, and resilient means for frictionally holding the tumblers to any position into which they are shifted.

2. In a cylinder-lock, the combination of 30 a casing, a carrier rotatable in the casing having a transverse guide-way extending therethrough, key-operable plate-tumblers transversely slidable in said guide-way and into interlocking relation with the casing and spring-plates between the tumblers.

EDWARD P. BAIRD.
